UNITED STATES PATENT OFFICE.

WILLIAM FISCHER, SR., AND WILLIAM VOGEL, OF PATERSON, NEW JERSEY,
ASSIGNORS, BY MESNE ASSIGNMENTS, TO WILLIAM FISCHER, SR., FRANK
FISCHER, AUGUST FISCHER, AND WILLIAM FISCHER, JR., OF SAME PLACE.

MACHINE FOR CUTTING DOUBLE-PILE FABRICS.

SPECIFICATION forming part of Letters Patent No. 655,674, dated August 7, 1900.

Application filed March 2, 1900. Serial No. 7,100. (No model.)

To all whom it may concern:

Be it known that we, WILLIAM FISCHER, Sr., and WILLIAM VOGEL, citizens of the Empire of Germany, residing in Paterson, in the 5 county of Passaic and State of New Jersey, have invented certain new and useful Improvements in Machines for Cutting Double-Piled Fabrics, of which the following is a specification.

10 This invention relates to a machine for cutting double-piled fabrics after they have been woven in the well-known double-pile looms, said cutting-machine being so arranged that the uncut double-piled fabric is fed continuously under uniform tension to a cutting-blade and the separated fabrics then wound upon independent rolls, so that one machine can be used for cutting the output of a number of looms without requiring a separate 15 pile-cutting device for each loom.

The invention consists of certain features of construction and combinations of parts to be hereinafter described and then claimed.

In the accompanying drawings, Figure 1 25 represents a front elevation of our improved machine for cutting double-piled fabrics. Fig. 2 is a vertical longitudinal section of the same on line 2 2, Fig. 1. Fig. 3 is also a vertical longitudinal section through the cutting 30 mechanism of the machine, drawn on a larger scale and showing the construction of the sharpening devices for the endless cutting-knife; and Fig. 4 is a detail vertical section of one end of the fabric-guiding blocks and 35 their adjusting mechanism.

Similar letters of reference indicate corresponding parts.

Referring to the drawings, A represents the supporting-frame of our improved machine 40 for cutting double-piled fabrics. At opposite sides of the frame A are supported on bracket-bearings A' the shafts of a driving-pulley B and a guide-pulley B', over which is stretched an endless horizontal cutting-knife C. The 45 length of the horizontal portions of the cutting-knife C is greater than the width of the double-piled fabrics to be cut. Rotary motion is transmitted to the driving-pulley B of the endless cutting-knife C by a suitable belt- 50 and-pulley transmission from an overhead

shaft, the bearings B² of the guide-pulley B' being made adjustable and spring-cushioned, so as to impart the proper degree of tension to the endless cutting-knife. The upper horizontal portion of the endless cutting-knife C 55 is used for pile-cutting purposes and is for this purpose guided between antifriction-balls d, that are placed in corresponding recesses d² of a guide-block D, which is composed of two sections D', that are recessed at 60 their adjacent faces, as at R, for guiding the upper horizontal portion of the endless cutting-knife C. The sections D' of the guide-block D are supported by angle-irons D², which are attached to the frame by suitable 65 fastening-screws. The antifriction-balls d are adjusted toward the knife C by means of set-screws d', which are slightly concave at their inner ends, so as to bear on the antifriction-balls and press them against the knife 70 C. The recesses d² serve to retain the antifriction-balls in position when the endless cutting-knife C is removed from the guide-blocks D' for repairs or otherwise. When the cutting-knife is replaced in its proper position in the guide-blocks, the antifriction-rollers at each side of the knife are placed back into their proper relative position toward the knife, so that the knife is freely guided 75 and kept in straight position between them. 80 A number of antifriction-rollers are arranged over that portion of the knife which is used for the cutting of the double-piled fabrics, as shown in Fig. 1, so that this portion after the set-screws and antifriction-balls are carefully 85 set is guided in a straight line and serves to cut off the fabric by its sharp edge in an accurate and even manner. The lower portion of the endless cutting-knife, between the driving and guiding pulleys B B', is moved 90 through between a number of suitable sharpening devices E, each of which is composed of two pivoted and spring-actuated sharpening-blocks e e, of roughened steel, emery, or other suitable material, which are supported 95 in suitable brackets E' of the frame A and which continuously sharpen the edge of the cutting-knife before it is used again for cutting the double-piled fabrics.

The double-piled fabric F is wound up in 100

certain lengths on roller F' as it is delivered from the double-pile loom and transferred on this roll to the pile-cutting machine. The double-piled fabric is conducted from the 5 roll F' over a stretching-roll f, through the throat of adjustable guide-blocks F², and over tension-rollers f' f² to feed-rolls G G', which are provided on their circumferences with fine needles that pierce the individual layers 10 of the double-piled fabric, so as to feed the same forward to a narrow throat formed between two triangular stretching-blocks H H'. The apices of the triangular blocks are adjacent to each other respectively above and 15 below the fabric F. The edge of the cutting-knife C is arranged close to the apices of the stretching-blocks H H', so that as the double-piled fabric passes through the throat between the blocks H H' the pile is 20 cut and each individual fabric guided in opposite directions over the outer sides of the stretching-blocks H H'. The stretching-blocks H H' can be vertically adjusted relatively to the edge of the cutting-knife by 25 set-screws h h, arranged in stationary keepers H², as shown in Fig. 4, said keepers being attached to the supporting-frame A. The cut fabrics are then taken up by a second set 30 of feed-rolls I I', provided with fine needles that pierce the fabrics and conduct them to the winding-up rolls L L'. For the purpose 35 of facilitating the clearing of the separated fabrics from the needles of the feed-rolls I I' endless canvas aprons I² I³ are used, which are passed over the feed-rolls I I' and over 40 the guide-rollers i i' and which by the motion imparted to them serve to clear the pile fabrics from the needles of the stretching-rolls I I', the canvas aprons slipping easily from 45 the needles and carrying thereby the piled fabrics along, so as to produce the effective clearance of the fabrics from the needles of the feed-rolls I I'. The fabrics then pass onto the winding-up rollers L L', on which 50 they are wound up. Uniform motion in opposite direction has to be imparted to the feed-rollers I I'. This is accomplished by a gear-wheel n on the shaft of the upper feed-roll I, which meshes with a pinion n', said 55 pinion imparting rotary motion to the second pinion n² and the latter again rotary motion to a gear-wheel n³ on the shaft of the lower feed-roll I', said gear-wheel being of the same size as the gear-wheel n and located vertically below the same, so that the lower roll I' is rotated at the same speed but in opposite direction to the upper roll I. The shaft of

the upper roll I receives rotary motion from a belt-and-pulley transmission, while rotary motion is imparted to the winding-up rolls L L' from the shafts of the rollers I² I³ by belt-and-pulley transmissions. A friction-brake 60 M is applied to an arm m, which is attached to one of the supporting-standards A² of the upper rolls, said friction-brake being pressed 65 with greater or less pressure on the winding-up rollers, so as to retard the motion of the same and produce thereby the loose winding of the fabrics on the winding-up rolls, so as to prevent the injuring or crushing of the 70 pile, which in the case of velvets, pluses, &c., is of considerable importance.

Having thus described our invention, what we claim as new, and desire to secure by Letters Patent, is—

75

1. In a machine for cutting double-piled fabrics, the combination of an endless pile-cutting knife, a longitudinally-grooved guide-block, said block being formed with recesses at the sides of its groove, antifriction-balls 80 arranged in said recesses, and upon which the cutting-knife has bearing, and means for sharpening that portion of the knife-edge of the cutting-knife which is out of action, substantially as set forth.

85

2. In a machine for cutting double-piled fabrics, the combination, of an endless pile-cutting knife, with means for guiding the cutting portion of the same, said means being formed of guide-blocks having a guide-groove for the cutting-knife, antifriction-balls located in recesses of said guide-blocks, adjacent to said groove for the cutting-knife, and set-screws for adjusting said antifriction-balls, substantially as set forth.

95

3. In a machine for cutting double-piled fabrics, the combination of an endless pile-cutting knife, means for feeding the double-piled fabric toward said cutting-knife, means for winding up the separated fabrics, and 100 means for pulling the latter taut, the same comprising two toothed feed-rolls, two guide-rollers, and endless aprons trained over the feed-rolls and guide-rollers, which aprons frictionally bear against the separated fabrics, substantially as set forth.

105

In testimony that we claim the foregoing as our invention we have signed our names in presence of two subscribing witnesses.

WILLIAM FISCHER, SR.
WILLIAM VOGEL.
